UNITED STATES PATENT OFFICE.

ABRAHAM RIVERA, OF SONSONATE, SALVADOR.

COLLAPSIBLE AND PORTABLE TOILET-SEAT COVER.

1,156,629.

Specification of Letters Patent. Patented Oct. 12, 1915.

Application filed June 9, 1915. Serial No. 33,080.

To all whom it may concern:

Be it known that I, ABRAHAM RIVERA, a citizen of the Republic of Salvador, and a resident of Sonsonate, in the Republic of El Salvador, Central America, have invented a certain new and useful Improvement in Collapsible and Portable Toilet-Seat Covers, of which the following is a specification.

- This invention relates to an improvement in toilet seat covers, and contemplates as a principal object the provision of an auxiliary sanitary cover which may be used in connection with toilet seats of ordinary and of various special construction, the auxiliary seat or cover being so constructed that it may readily be folded for transportation and when so folded will occupy a minimum amount of space so that it may readily be carried in a grip or satchel.
- 20 A further object of the invention is to provide a seat cover of the class described in the nature of a plurality of hingedly connected sections or segments, the segments forming the rear portion of the cover being provided with a latching means whereby the segments will be maintained in relatively rigid position when the cover is in use, so that collapse of the cover will be prevented.

A further object of the invention is to provide a device of the class described which will be extremely simple, durable, efficient in operation, and inexpensive to manufacture.

With these and other objects in view which will become apparent as the description proceeds, the invention resides in the construction, combination, and arrangement of parts hereinafter more fully described and claimed, and illustrated in the accompanying drawing in which like characters of reference indicate like parts throughout the several figures, of which—

Figure 1 represents a plan view of a seat cover constructed according to my invention. Fig. 2 represents a view in section taken on the plane indicated by the line 2—2 of Fig. 1, looking in the direction indicated by the arrow. Fig. 3 represents a view in section taken on the plane indicated by the line 3—3 of Fig. 1. Fig. 4 represents a view in section taken on the plane indicated by

the line 4—4 of Fig. 1. Fig. 5 represents a perspective view of the device in folded or collapsed position.

Referring more particularly to the drawing, it will be noted that the seat cover consists of the forward or front segments 5 and 6 and the rear segments 7 and 8. When the seat cover is extended and is in operative position as indicated in Fig. 1, it will be noted that it is substantially of the form of an ordinary closet seat.

The front segments 5 and 6 are connected together along their adjacent abutting edges by means of a double leaf hinge 9. The leaves of the latter, it will be noted, by reference to Fig. 3, are countersunk in the adjacent abutting ends of the segments 5 and 6, so that when the seat cover is in extended position, these ends will abut tightly one against the other so as to provide a close joint. The segments 5 and 7 constituting one half of the seat cover, and the segments 6 and 8 constituting the other half, are respectively connected together by means of the hinges 10. By referring to Fig. 2 it will be seen that the leaves of the hinges 10 are countersunk in the under faces of the segments, rather than in the end faces thereof, as is the case with hinge 9. In this manner the adjacent edges of segments 5 and 7 and 6 and 8 respectively may abut and bear against each other when the seat cover is extended, and will be prevented from collapsing downwardly.

85 The adjacent edges of the segments 7 and 8 are not hingedly connected together, but are adapted to be engaged together when the device is in extended position through the medium of a latching mechanism. This 90 mechanism includes a rigid bar of metal 11 provided with an enlarged head 12 at its outer end. The bar is pivoted at its inner end in a recess 13 cut in the rear edge of segment 7 by means of a bolt or screw or other suitable device 14. A similar recess 15 provided in the rear edge of segment 8 includes an enlarged portion 16 in which the head 12 of the latch is adapted to engage when the cover is in extended position as 100 indicated in Fig. 1. This latch thus extends transversely of the seat when the lat-

ter is extended, and will prevent the seat from collapsing along its longitudinal axis or diameter.

The latch is provided adjacent its enlargement or head with an outwardly extending spur or thumb hold 17 by means of which said latch may readily be engaged for withdrawing it from the recess in segment 8 when the device is to be folded.

10 The line upon which the hinges 10 are arranged occurs in advance of the central transverse axis of the cover, and hence the weight and strain exerted upon the cover will not occur directly along the lines occupied by the hinges. The arrangement of these hinges 10 will prevent collapse of the device along its transverse axis when in extended position, and the latch 11 will prevent collapse of the device along its longitudinal axis, and will furthermore connect the rear segments of the cover closely together so as to provide a tight and compact joint between them.

When not in use the latch may be disconnected from segment 8 and the device may be folded into the position shown in Fig. 5 so as to occupy but a small space. When so folded the device may be readily carried about in a suitcase or traveling bag.

30 Although I have described the preferred embodiment of my invention, I may desire to make such changes in the construction, combination, and arrangement of parts thereof, as do not depart from the spirit of

the invention and the scope of the appended claims.

It will be noted that I have provided a hygienic portable toilet seat.

I claim:

1. A toilet seat cover comprising a pair of forward and a pair of rear segments, a hinge connecting the forward segments along the longitudinal axis of the cover, said hinge having its leaves countersunk in the adjacent ends of the forward segments, hinges connecting the forward segments with the rear segments along lines in advance of the transverse axis of the device, said last hinges being secured to the under faces of the forward and rear segments, and a latch pivoted within a recess in the rear edge of one of the rear segments and provided with a head, said latch being adapted to be engaged within a recess provided in the rear edge of the opposite rear segment for bracing the cover in position along its longitudinal axis, and a thumb hold provided on the latch.

2. A toilet seat cover comprising forward and rear segments hingedly connected together along lines to one side of the transverse axis of the cover, the forward segments of the device being hingedly connected together, and a latch pivotally connected to one of the rear segments and being adapted to detachably engage the opposite rear segment for bracing the cover against collapse along its longitudinal axis.

ABRAHAM RIVERA.
